* cited by examiner

Primary Examiner — Stacia A Cadmus(74) *Attorney, Agent, or Firm* — Mannava & Kang, P.C.; Arash Behravesh(57) **CLAIM**

The ornamental design for a top portion of a spoke of a wheel, as shown and described.

DESCRIPTION

FIG. 1 is a perspective view of a top portion of a spoke of wheel showing a new design; and,

FIG. 2 is a front view thereof.

In the drawings, the broken lines depict environmental subject matter only and form no part of the claimed design.
